US00D631057S

(12) **United States Design Patent**
Kuo

(10) **Patent No.:** **US D631,057 S**
(45) **Date of Patent:** **** Jan. 18, 2011**

(54) **DATA CARD**

(75) Inventor: **Ling-Mei Kuo**, Tu-Cheng (TW)

(73) Assignee: **Chi Mei Communication Systems, Inc.**, Tu-Cheng, Taipei County (TW)

(**) Term: **14 Years**

(21) Appl. No.: **29/358,028**

(22) Filed: **Mar. 22, 2010**

(30) **Foreign Application Priority Data**

Dec. 17, 2009 (CN) 2009 3 0329546

(51) **LOC (9) Cl.** **14-02**

(52) **U.S. Cl.** **D14/480.7**

(58) **Field of Classification Search** D14/411, D14/433, 435.1, 436, 480.1–480.7, 484.1, D14/137, 155, 167, 168, 203.1–203.8, 240, D14/242, 299; D3/201, 273; D13/107, 108, D13/149, 184; 710/300, 301; 439/131, 135–147
See application file for complete search history.

(57) **CLAIM**

The ornamental design for a data card, as shown and described.

DESCRIPTION

FIG. 1 is a perspective view of a data card showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is a perspective view thereof, wherein the data card is shown in an extended configuration.

The broken line showing of the USB connector in FIGS. 1, 5, and 8 are for the purpose of illustrating unclaimed portions of the data card and form no part of the claimed design.

1 Claim, 8 Drawing Sheets

FIG. 1

FIG. 2

FIG. 3

FIG. 4

FIG. 5

FIG. 6

FIG. 7

FIG. 8
